KEG CLOSURE

Victor Alvear, Clifton, N. J.

Application October 17, 1945, Serial No. 622,795

5 Claims. (Cl. 217—98)

1

This invention relates particularly to bungs for beer kegs and the like.

In the ordinary keg when it is desired to empty the contents, the stopper, which is usually in the form of a cork, is knocked out of the bung hole and often becomes lost or damaged necessitating replacement, which is costly and inconvenient.

Sometimes also the cork remains in the keg after it has been washed and resort is had to spearing the cork in order to recover it with resultant damage to the keg. Leakage is also liable to develop around the ordinary cork and it is sometimes accidentally blown out.

It is an object of the present invention to provide a bung for a keg in which the stopper is a fixture on the keg and cannot become lost and the chance of its becoming damaged is reduced to a minimum.

Another object is to provide means for bringing the stopper or plug to alignment with the bung hole by gravity where it can easily be moved into closed position.

Another object is to provide a stopper with means for readily grasping it with a tool and with means for sealing the opening in the bung.

Another object is to eliminate hammering and pounding on the barrel head and to eliminate spearing of corks.

Another object is to facilitate tapping of the keg.

Another object is to provide a stopper that is sanitary, simple in construction and economical to manufacture.

Another object is to provide a stopper that cannot leak or blow out regardless of the pressure in the keg thereby providing an air-tight seal.

Another object is to provide a stopper that is self-sealing.

In the drawing, Fig. 1 is a sectional view of the improved ring with the plug in position in the ring and the pendulous member which carries the plug.

Fig. 1a is a side view of a tool for drawing the plug into closing position.

Fig. 2 is a view of the tool of Fig. 1a showing how it is connected to the plug.

Fig. 3 is an inside end view of the plug.

Fig. 4 is an end view of the tool.

Fig. 5 is another sectional view of the ring with the pendulous member and plug tilted out of position.

Fig. 6 is a side view of the pendulous member.

Fig. 7 is a plan view of the ring.

The keg 6 has a screw threaded opening 7 into which the metallic ring 8 is screwed. The latter

may have bayonet slots 9 for the insertion of a tool for inserting and removing the ring. The ring has a central passage 10 preferably circular in cross-section.

5 The plug 11 formed of a resilient material such as nylon plastic which is durable and not affected by the liquid in the keg and adapted to fit the passage in the ring. This plug is mounted on a rod 12 which is carried by a pendulous carrier member 13 pivoted at 14 on the inner surface of the ring 8. The projecting side arms 15, 15 serve to slidably support the rod 12. The mass of the carrier member is so disposed as to hang with the plug and its rod vertically and in line with the passage in the ring when the ring is horizontal. The carrier member may be provided with an enlarged portion on its lower end as shown. The rod 12 has a projection 16 on the end to serve as a stop to prevent the rod and plug from being detached. The plug has a flange 17 which abuts against the inner edge of the passage 10 when the plug is in place. The plug may have a chamber 18 so that the pressure in the keg acting against the wall of the chamber assists in holding the plug in position.

When the carrier member is swung to vertical position and the upper end of the plug 11 enters the lower end of passage 10 in the ring member, the pressure of gas within the keg will force the plug upwardly until the flange 17 engages the lower edge of the passage in the ring.

The plug is pushed inwardly by a draw rod used for drawing liquid from the keg. To replace the plug, a tool 20 such as shown in Figs. 1, 2 and 4 can be used. Here the jaws 21 are shaped to grip the knob 19 of the plug. It is merely necessary to insert the tool into the passage 10 in the ring 8, then hook the jaws sidewise into engagement beneath the knob and then pull the plug 11 outwardly into the passage 10.

I claim:

1. A metallic ring having a pendulous member hinged to said ring, a plug for fitting the hole in said ring and having a rod connected to said plug, said pendulous member having a lateral projection slidably supporting said rod and plug.

2. A metallic ring having a rigid pendulous member hinged to the inner surface, a plug for fitting the hole in said ring and spaced arms carried by said pendulous member and swingable therewith for slidably supporting said plug in all positions, said plug having a flange for seating against the inner rim of the hole in said ring, when moved to hole-fitting position.

3. A metallic ring having a rigid, pendulous

member hinged to the inner surface, a plug for fitting the hole in said ring and spaced supports integral with said pendulous member for slidably supporting said plug in aligned position with said hole for movement into or out of said hole and for supporting said plug when moved away from said hole.

4. A keg closure comprising a ring for insertion into an opening in the wall of a keg and having a passage, a pendulous member hinged at one end to said ring at one side of said passage and normally depending into said keg, a rod slidably carried by said pendulous member normally in alignment with said passage and a plug carried on one end of said rod for sealing said passage, the relative arrangement of the pendulous member, rod and passage being such that when the pendulous member is swung to normal dependent position the plug is initially swung into alignment with the passage in the ring in position to be auto-

10

matically forced by the pressure of gas within the keg into said passage for sealing the same.

5. A keg closure as defined in claim 4 in which the pendulous member is provided with an enlargement at its free end for urging and holding the slidable rod and plug in normal aligned position with the passage in the ring.
